NEBULIZER

Girard B. Robinson, Mount Gilead, Ohio, assignor to
The Dr. Nathan Tucker Laboratory

Application April 25, 1957, Serial No. 45,882

Term of patent 14 years

(Cl. D83—1)

Fig.1

Figure 1 is a side elevational view of a nebulizer with the inhaling tube stopper removed, embodying my new design;

The dominant features of the new design are shown in solid lines in the drawing.

I claim:

The ornamental design for a nebulizer, substantially as shown and described.
